SLUG DETECTOR

William C. Mitchell, Stratford, Conn.

Application March 9, 1936, Serial No. 67,826

5 Claims. (Cl. 194—100)

This invention relates to new and useful improvements in coin controlled apparatus and has particular relation to a means for detecting "slugs".

5 An object of the invention is to provide a means for preventing operation of nickel (five cent coin) controlled devices unless a nickel is inserted into such devices, or to separate slugs from nickel coins.

10 Other objects and advantages will become apparent from a consideration of the following detailed description taken in connection with the accompanying drawings wherein satisfactory embodiments of the invention are shown. However,

15 it will be understood that the invention is not limited to the details disclosed but includes all such variations and modifications as fall within the spirit of the invention and the scope of the appended claims.

20 In the drawings:

Fig. 1 is a view partly in elevation and partly in section and showing one form of the invention;

25 Fig. 2 is a sectional view taken substantially along the line 2—2 of Fig. 1;

Fig. 3 is a sectional view taken substantially along the line 3—3 of Fig. 1;

Fig. 4 is a view partly in section and showing a modified construction;

30 Fig. 5 is a view at right angles to Fig. 4;

Fig. 6 is a sectional view taken substantially along the line 6—6 of Fig. 4;

Fig. 7 is a view partly in section and partly in elevation, and showing another modification;

35 Fig. 8 is a sectional view taken substantially along the line 8—8 of Fig. 7.

The present invention is based on the discovery that if certain metals, preferably high carbon

40 steels, are rubbed across a nickel (a United States five cent coin) or if the nickel is rubbed across such metals an electric current, sufficient to operate a sensitive high speed meter, as a galvanometer or milliammeter, is generated. My

45 tests indicate all kinds of iron and steels in particular have this effect, and it seems the harder the steel or closer the grain the better is the effect. The high carbon steels are particularly good, such as that used for phonograph needles. Steel like

50 drill rod, high speed, tool and machine steels worked well. I have also found the copper-nickel-zinc alloy known as "22% nickel silver" worked fairly well and thus indicates there are probably other specific alloys which could be used.

55 The movement of the arm or pointer of the meter

due to the energizing of the meter by the generated current can be used to release the mechanism being guarded and which mechanism may be a telephone, dispenser, etc.

I have found that the wiping of the high carbon steel or similar material across any of the ordinarily easily available metals or alloys other than that of alloys composed principally of large proportions of both copper and nickel and especially the alloy containing a large amount of 10 copper and nickel of which five cent coins are made will not generate sufficient current to operate the meter. The various common metals available and from which slugs are usually made cannot be used to generate the necessary current. 15 This is true of pure nickel, cobalt, and of various brasses from low to high brass, bronzes and coppers. White gold will give about one-fifth of the effect of the nickel coin.

20 Various arrangements of trip mechanisms may be employed or associated with the pointer or arm of the meter employed so as to be controlled thereby. Three arrangements are shown in the accompanying drawings although it is to be understood that the invention is not limited to the 25 particular arrangements disclosed.

Referring now particularly to Figs. 1, 2 and 3, at 10 is shown a casing or housing having therein a substantially Y-shaped chute including a vertically disposed main arm or passage 11 and outwardly inclined passages or arms 12 and 13 at the lower end of the passage 11. At the upper end of the passage 11 is a housing 14 forming a cross passage 15 in communication with passage 11, and operable in the passage 15 is a slideable device or carrier 16 including a metal block or plate 17 having a slot or opening 18 extending vertically through it and of a size to receive a nickel coin 19.

30 The plate 17 is shiftable from the full line 40 position of Fig. 1 to the dotted line position thereof, and when the plate is in the full line position its slot 18 is registering with a slot 20 in the upper wall of the housing 14 so that the coin 19 may be inserted in the slot 18 through the upper end thereof. On the plate being shifted to the dotted line position the lower end of its slot 18 registers with the upper end of the chute arm 11 so that the coin falls into such chute arm. In one side wall the plate 17 has a horizontally disposed slot 21 entering into the slot 18 but also extending beyond the vertical edges thereof, and about the edges of the slot 21 electrical insulating material 22 is arranged.

35 One side of the housing or casing is expanded 55

laterally providing a housing portion 23 at the slotted side of the plate 17. Within such housing portion a spring arm 24 is mounted as on a support 25 and the outer or free end of such arm carries a pin 26 of high carbon steel or other suitable metal. This pin 26 has its inner end portion bevelled as at 29, and the pin extends through the slot 21 and under the urging of the spring 24 is normally maintained with its inner end in engagement with the wall of the plate opposite that having the slot 21. It is noted that except for this engagement of the inner end of the pin with the plate 17 the pin is insulated from the plate by the insulating strip 22 and by insulating the mounting 25 of the spring arm 24.

The housing mounting plate 17 has a tubular extension 30 through which a tube 31 enters the housing and the inner end of such tube 31 is threaded or otherwise secured to the plate 17.

About tube 31 a coil spring 32 is arranged, and such tube at diametrically opposite points is slotted at 33 to accommodate a pin 34 carried by the inner end of a rod 35. Pin 34 extends at opposite sides of the tube 31 so that on the rod 35 being forced forwardly in the tube the spring 32 will be compressed if slide 17 does not move. The outer end of rod 35 is secured to a head 36 and the latter is in turn secured to a sleeve 37 adapted to be telescoped over the housing extension 30 as will later appear. Within such sleeve and about the rod 35 is a spring 38 bearing at one end against the outer end of the tubular housing extension 30 and at its other end against the head 36.

It is noted that while the pin 26 is in normal position it extends across one edge of a coin 19 inserted in the slot 18 and being in the path of movement of the coin tends to prevent movement of the plate 17 in a direction to carry the coin over the chute 11. The spring 38 normally keeps the head 36, sleeve 37 and rod 35 in the outer position shown in Fig. 1, and the pin 34 at the inner end of the rod engaging the outer ends of the slots 33, the sleeve 31 and plate 17 are kept in normal position.

When a coin has been placed in the slot 18 the head 36 is pressed inwardly telescoping the sleeve 38 over the housing extension 30 and moving the rod 35 inwardly. As the rod moves inwardly it acts through the pin 34 to cause compression of the spring 32. Up to a certain point, the pin 26 being across the forward edge of the coin 19, inward movement of the coin and of the plate 17 is prevented. However, the edge of the pin toward the coin is bevelled and when the spring 32 has been sufficiently compressed so as to overcome the holding action of the pin 26 the latter is cammed outward as to the dotted line position of Fig. 3 and the spring 32 expanding snaps the plate 17 and the coin 19 to an inner position disposing the coin over the upper end of the chute 11.

As the coin is thus shifted inwardly it is rubbed across the inner end of the pin 36 and an electric current is generated if the coin and pin are in a closed circuit. On release of the hand piece 36 the plate or slide 17 and its associated parts are returned to normal position by the spring 38 although it will be understood that before this occurs the coin drops out of the slot 18 into the chute 11.

A wire 39 connects the spring 24 and thereby the pin 26 with the coil 40 of a suitable galvanometer or meter 41 while a wire 42 connected with the plate 17 also connects with such coil 40.

From this it will be clear that when the pin 26 is in engagement with such plate the coil 40 is short circuited preventing the coil and needle from swinging from a jar or the like. The meter 41 also includes the usual permanent magnet shown as a horse shoe magnet 43 and further includes a needle or arm 44 adapted to be shifted on energizing of the coil 40. In this connection it will be appreciated that with the arrangement shown any current generated by the wiping of the coin 19 across the pin 26 will be impressed on the coil of the meter 41 so as to cause shifting of the arm 44.

A bar or lever 45 is provided with a pivot 46 mounted in the bearings 47 and it is noted that such pivot 46 is arranged at right angles to the pivot 48 carrying the meter pointer or arm 44 and in turn mounted in bearings 49. The bar 45 extends along one side of the coin chute and toward one end carries a pin 50 projecting into the coin chute through an arcuate slot 51 and normally occupying a position extending across the branch 12 at the upper end thereof as shown by the full lines in Fig. 1. The end of the bar opposite that carrying pin 50 is counterweighted as at 52 and extends under the meter arm 44 when the latter is in its normal full line position. When bar 45 is in its normal horizontal position its counterweighted end is resting on a stop pin 53 and is at the underside of the arm 44 so that the bar is held against movement about its mounting pivot.

Extending across the upper side of the meter arm 44 is a bar 54 mounted as on supports 55 and such bar backs up and prevents vertical movement of the arm 44 under action of bar 45, although it is to be understood that there is no engagement between these parts unless the arm is forced upwardly against the bar. Secured to and extending downwardly from the weighted end 40 of the bar 45 is a curved wire or tail 56 the purpose of which will later more fully appear.

When using the apparatus a coin, as the coin 19, is placed in the slot 18 and thereafter the head 36 is pressed inwardly. This results in spring 38 being compressed, and as the rod 35 and its pin 34 are moved inwardly spring 32 is compressed and is pressing inwardly on the plate 17 so that the coin 19 is being forced against the pin 26. When the spring 32 has been compressed to such an extent that the pressure exerted by it is sufficient the engagement of the coin with the inclined or cammed end 39 of the pin 26 results in the latter being forced into the dotted line position of Fig. 3 and the spring 32 being then free to expand snaps the plate 17 from the full to the dotted line position of Fig. 1. The coin 19 is carried with the plate into a position over the upper end of the chute 11 and as the coin is thus shifted it is wiped across the inner end of the pin 26. If desired the inner ends of slots 33 may be positioned so as to be engaged by pin 34 just before the limit of its inward movement so as to give a positive push or start to slide 17 and then its inward movement will be completed under action of spring 32.

If the coin is a nickel (a United States five cent piece) an electrical current is generated and is impressed on the coil of the galvanometer or meter 41 with the result that the meter arm 44 is shifted from the full line position extending over the counter-weighted end of bar 45 to the dotted line position beyond the end of said bar. Therefore on the meter being energized its arm 44 is carried out of a position locking the bar 45.

and such bar may be tilted into the position suggested by the dotted lines in Fig. 1. The bar 45 does not move of its own accord on shifting of the needle arm 44 but the bar is released and the coin dropping through the chute part 11 strikes the pin 50 and causes the bar 45 to rock shifting the pin downwardly in the slot 51 so as to carry it out of the chute portion 12 and permit the coin to pass downwardly through such chute portion. The coin as it passes down chute 12 may be used to release or trip any desired mechanism such for example as a dispensing mechanism, close a telephone circuit connection, etc., as desired.

As the coin rocks the bar 45 the tail 56 is carried with the bar into a position in the path of the return movement of needle arm 44 thus preventing the arm 44 from making its return movement until the bar drops, since such arm as it tends to return to normal position engages the tail 56 and is prevented from moving under the counter-weighted end of the bar. When the coin moves beyond the pin 50 the bar rocks back to normal horizontal position and as it reaches such position the meter arm 44 is free to return to normal position extending across the upper side of the counter-weighted end of the bar.

When the coin fed to the machine is other than the United States nickel or five cent piece an electrical current sufficient to operate the meter is not generated by the wiping action between such coin and the pin 26 and therefore the meter 41 will not be energized and its arm 44 will remain in position extending across the upper side of the bar 45, the needle arm 44 being backed up by bar 54 against upward pressure of lever or bar 45. Thus when the coin offered drops on to the pin 50 the latter will be held against movement and the coin will be prevented from moving down the chute arm or portion 12 but will be caused to move down the arm or portion 13 which may conduct it to a suitable receptacle or return it to the outside of the machine as desired. From this it will be understood that after a coin is presented to the machine the meter 41 determines the further disposition of the coin, and if the coin is a nickel it moves along one path and if it is not a nickel it is caused to move along some other path.

My experiments with the present invention have led to the conclusion that it is only by the wiping action between a nickel coin and the pin 26 or its equivalent that an electrical current sufficient for the present purpose will be generated. If a slug of any other ordinary metal or alloy, at least of the kinds of which slugs are usually made, is inserted into the machine the necessary electrical current will not be generated. Pure nickel, cobalt, and all kinds of brasses from the low to high brass bronzes and coppers have been tried without success. The only coin or the only metal I have found from testing a large number of metals and alloys available which gives the desired results are alloys composed of large proportions of both copper and nickel, and by far the best results and greatest meter arm movement were secured with the special alloy, or one similar to it, used in making the United States nickel or five cent coin, and it is to be understood that in this application the word "nickel" refers to the coin of the United States known by that name or to a slug made from the alloy of that coin. While the pin 26 or the equivalent part which is to have a wiping action with the coin so as to generate the necessary electrical current is preferably of high carbon steel something like that of a phonograph nee-

dle), the invention is not limited to this particular metal since other irons and steels as mentioned above and possibly other metals may be used with reasonably satisfactory results.

Referring now to Figs. 4, 5 and 6 a portion of a housing or casing is shown at 60 and the same is provided in its upper end with a slot 61 leading into a vertically disposed chute portion 62 having diverging branches 63 and 64 at its lower end corresponding with the chute portions 11, 12 and 13 of Fig. 1 first described. Within the housing 60 and arranged at right angles to and entering and extending at each side of the chute portion 62 is a slot 65.

Accommodated by the slot 65 and extending part way in to the chute 62 from opposite sides thereof are a pair of metal shoes 66 and 67 mounted as by pins 68 located in slots 69. Light leaf springs 70 carried by the shoes 66 and 67 bear against blocks of insulation 71 and normally act to urge the shoes toward one another and this tendency of the springs is checked or limited when the pins 68 are in the inner ends of the slots 70 as shown in Fig. 4. Insulating pieces 72 located in the slot 65 at opposite sides of the chute 62 are pivotally mounted at 73 and secured to the respective pieces and extending upwardly from them are conducting bars or wires 74 and 75 at their upper ends carrying curved inwardly directed contact pieces 76 and 77 normally in engagement. Straps 78 and 79 electrically connect the shoe 66 with the conductor 74 and the shoe 67 with the conductor 75, respectively.

Wires 80 and 81 corresponding respectively with the wires 39 and 42 of Figs. 1 through 3 serve to connect the shoes 66 and 67 with the meter 41. Secured to the insulating pieces 72 and extending downwardly from them are bars or wires 82 and 83 at their lower ends carrying curved inwardly directed cam pieces 84 and 85 adapted to be brought into engagement or sufficiently close to be shifted by the coin as will later appear. Since the contact pieces 76 and 77 are normally in engagement and the bars or wires 74 and 75 are connected with the respective shoes by the straps 78 and 79 and such shoes are connected with the coil in the meter by the wires 80 and 81 it will be apparent that such meter coil is normally in a closed circuit and therefore shorted so it will not swing under a jar or movement of the box or case carrying the device.

On insertion of the coin (nickel or slug) 86 through the slot 61 it engages the contacts 76 and 77 and forces them apart or outwardly causing rocking of the insulating pieces 72 about their pivots 73 and this movement of the insulating pieces causes the bars or wires 82 and 83 to be swung toward one another whereby the cams 84 and 85 carried by such bars or wires are moved inwardly toward each other. The shoes 66 and 67 are spaced apart a distance slightly less than the thickness of a nickel and the tension of the springs 70 is so adjusted that a nickel passing between the shoes makes a good contact with them but is yet permitted to fall between them.

Both of these shoes may be of high carbon steel or one shoe may be of high carbon steel while the other is of some other metal such as for example copper, it being understood that one shoe is of the material of pin 26 and has the same effect. As the nickel moves downwardly between the shoes it wipes against them and a current is generated and impressed on the coil of the meter so as to have the meter act in the manner previously described. If the coin is a

slug or of other metal than the alloy of the United States five cent piece no current will be generated and the galvanometer or meter needle will not be shifted. It will be apparent that the meter may control any desired tripping mechanism but as suggested here the bar 45 and pin 50 and the associated mechanism of Figs. 1 through 3 may be employed in connection with the generating means of Figs. 4, 5 and 6. As the nickel passes from between the lower ends of the shoes it engages the cams 84 and 85 forcing them apart in a manner to rock the insulating pieces 72 about the pivots 73 so as to carry the contacts 76 and 77 back into engagement to 15 again short circuit the meter coil.

Figs. 7 and 8 show yet another modification wherein an apparatus embodying the principles of the invention is shown in which the steel contact is wiped across the coin instead of the coin moving over the contact. It is shown as arranged in association with a pay station telephone but this is merely illustrative as it may be used to control any other type of coin controlled device. In these figures a housing or casing 90 is provided with a coin entrance slot 91 leading to a vertical chute portion 92 from the lower end of which extend diverging chute portions 93 and 94 corresponding with the chute portions 11, 12 and 13 of Fig. 1. A pair of dogs 95 each pivoted as at 96 are normally held in positions extending into the chute 92, by means of coil springs 97, and each such dog includes an extension 98 maintained against a stop pin 99 whereby movement of the dogs under the 35 influence of the springs is limited.

An arm 100 extends at one side of the chute 92 and such arm is carried by pivot 101 about which is arranged a spring 102 having an end portion 103 extending beneath the arm 100 and 40 normally tending to shift the arm to the dotted line position of Fig. 7 and to maintain it in such position. This arm 100 includes a section 104 which may be described as the pivoted section and further includes an outer section 105 hinged 45 to the section 104 at 106 and normally these sections are held in alignment by a spring 107 bearing against the outer portion of section 105. The arm 100 is electrically insulated from the casing 90.

50 Such arm section 105 carries a pin 108 formed of high carbon steel or its equivalent, and normally extending across the coin slot or the upper portion of chute 92. A stop pin 109 normally extends slightly across the upper side of the arm 100 so as to maintain it in the full line position of Fig. 7 with the spring 102 tensioned. Rigid with the arm 100 is a relatively long pin 110 extending outwardly through an arcuate slot 111 in the housing 90 and projecting into 55 a position at the underside of the hook 112 for a telephone receiver.

In the use of this apparatus a person desiring to use the telephone, for example, removes the receiver from the hook 112 and the latter moves 60 upwardly off the pin 110. Next a nickel 113 is inserted through the slot 91 and engaging the dogs 95 rocks them downwardly to the dotted line positions against the action of the springs 97. When the dogs are in the dotted line positions 65 the nickel may pass between them and into engagement with the pin 108. It is noted that this pin is beveled on its upper side at 108a as shown in Fig. 8 and when the nickel engages the pin the nickel has moved downwardly to such an 70 extent as to permit the dogs to be returned to 75

their normal positions by the springs 97. This places the dogs in positions preventing movement of the nickel upwardly out of the coin slot or preventing return movement of the nickel. As downward movement of the nickel continues it causes the arm section 105 to swing rearwardly about the hinge 106 as a pivot and against the action of the spring 107 thus also moving the pin 108 outwardly.

As the arm section 105 is thus swung from 1 beneath the stop pin 109 there is nothing further to hold the arm and the spring 102 swings the arm upwardly. As this occurs the pin 108 is wiped across the nickel being held against it by the spring 107 and an electrical current is generated. The dogs 95 prevent the coin being forced upwardly under this wiping action. Wires 114 and 115 corresponding with the wires 39 and 42 of Fig. 1 connect the casing 90 and the arm 100, respectively, with the meter so that any 20 current generated as described is impressed on the meter and the same actuated to release the bar 45 as previously set forth. After pin 108 is wiped across the coin this coin drops in chute 92 onto pin 50, and if it was a nickel so as to 25 generate current to operate the meter the lever arm 45 will be released as above described, permitting the coin to go down branch chute 93 to complete the telephone connection to the central office. When the user has finished with the 30 telephone he returns the receiver to the hook 112 and this draws the hook downwardly, and the latter engaging pin 110 moves it downwardly carrying the arm 100 back to normal position in which position it is again held by the pin 109 35 until the insertion of another coin shifts the arm section 105 from beneath such pin. In this position the end of pin 108 engages the casing 90 at the side of the coin chute and thus automatically short circuits the meter coil to prevent this coil 40 and its needle swinging by jars, etc.

If in this case the coin is not a nickel coin the meter will not be operated and the lever 45 will not be released the same as described in connection with the other forms.

It will now be understood that with each of the several devices shown, on the insertion or feeding of a nickel to the apparatus a current will be generated and impressed on a meter and the nickel permitted to pass through the proper path so as to release a coin controlled mechanism as a telephone, dispenser, etc. If any coin or slug other than a nickel is fed to the machine then an electrical current is not generated and the meter is not actuated and such other coin 55 or slug is directed along a different path and prevented from releasing the coin controlled mechanism which is being guarded. In each case the coil of the meter is short circuited so as to prevent anyone causing movement of the needle or arm 44 of the meter by thumping or otherwise 60 jarring the mechanism.

It will be clear that the relative wiping action between the coin and the member of a different metal, such as the member 26, 66 and 67, or 108, is 65 secured whether the member is shifted or wiped across the coin or the coin is shifted or wiped across the member, and therefore when the statement of the member being relatively wiped across a coin or similar statement is made, it is used in 70 a generic sense to mean either operation.

Having thus set forth the nature of my invention, what I claim is:

1. In a device of the character described for separating nickel coins from the usual slugs of 75

materially different metal, a coin slot including a pair of paths leading therefrom, an electric meter, means controlled by the meter to determine the path a coin in the slot will take, said means being arranged to normally cause the coin to take one path and when the meter is energized to cause it to take the other path, a member composed of high carbon steel, means arranged for causing a relative wiping action between the member and a coin in the slot, and means for electrically connecting said member and the coin with the meter during the wiping operation.

2. In a device of the character described, a coin slot including a pair of paths leading therefrom, an electric meter including a coil and an arm operated by the coil on energizing of the latter, means associated with the slot normally shorting the circuit of the coil, means controlled by said arm to determine the path a coin in the slot will take, said means being normally in a position to cause the coin to take one path and held in that position by the arm, a member composed of a different metal from that of the alloy of a nickel coin and having the characteristic of when relatively wiped across a nickel coin of generating sufficient electromotive force to energize the meter to shift said arm to release said path determining means and when wiped across the usual slug of a materially different metal of not generating sufficient electromotive force to operate the meter, means arranged for causing a relative wiping action between the member and a coin in the slot, and means electrically connecting said member and the coin in circuit with the coil during the wiping operation.

3. In a device of the character described for separating nickel coins from the usual slugs of materially different metal, a coin slot including a pair of paths leading therefrom, an electric meter, means controlled by the meter to determine the path a coin in the slot will take, said means being arranged to normally cause the coin to take one path and when the meter is energized to cause it to take the other path, a member composed of means including a steel contact, means arranged for causing a relative wiping ac-

tion between the contact and a coin in the slot with a rapid snap movement, and means electrically connecting the contact and the contact in circuit with the meter during the wiping operation.

4. In a device of the character described for separating nickel coins from the usual slugs of materially different metal, a coin slot including a pair of slots leading therefrom, an electric meter, means controlled by the meter to determine the path a coin in the slot will take, said means being arranged to normally cause the coin to take one path and when the meter is energized to cause it to take the other path, a steel pin projecting into the path of a coin fed to said slot, a spring to shift one of the elements consisting of the coin and the pin across the other, said pin being yieldingly mounted to hold against the coin until the spring is compressed so that the spring snaps the one element across the other with the pin wiping against the side of the coin, and means electrically connecting the pin and coin in circuit with the meter during the wiping operation.

5. In a device of the character described for separating nickel coins from the usual slugs of materially different metal, a coin slot including a pair of slots leading therefrom, an electric meter, means controlled by the meter to determine the path a coin in the slot will take, said means being arranged to normally cause the coin to take one path and when the meter is energized to cause it to take the other path, a steel pin projecting into the path of a coin fed to said slot, a member shiftable to carry a coin past said pin, a spring for shifting said member, hand operated means to compress the spring to have it shift the member from one position to the other, said pin being yieldingly mounted to hold the coin and member until the spring is compressed so that the spring shifts the member and coin with a snap action carrying the coin across the pin with the latter wiping against the side of the coin, and means electrically connecting the coin and pin in circuit with the meter during the wiping operation.

WILLIAM C. MITCHELL.
